UNITED STATES PATENT OFFICE.

JOHN W. MILLET, OF BATEHELLERVILLE, NEW YORK, ASSIGNOR TO HIMSELF, ISAAC NOYES, JR., AND THOS. C. FANNING.

IMPROVEMENT IN MODE OF MANUFACTURING TIN CANS, CADDIES, &c.

Specification forming part of Letters Patent No. 12,624, dated May 3, 1864.

To all whom it may concern:

Be it known that I, J. W. MILLET, of Batchellerville, county of Saratoga, and State of New York, have invented a new and Improved Mode of Manufacturing Boxes and Caddies; and I do hereby declare that the following is a full, clear, and exact description of the same, reference being had to the accompanying drawings, making part of this specification, in which—

Figure 1 is a central section of a box as manufactured by me.

I will now describe the manner in which boxes and caddies are made.

First, the tin or other metal plate is cut into the required strips and passed below the rollers of a coiling, crimping, and beading apparatus, and shaped as shown; secondly, the head or bottom is placed within the coil of the rim in

its proper place against the lap *a* of the rim; thirdly, the head and rim now united are next passed upon a form to correspond with the inside of the box or can and gripped by suitable jaws or their equivalent; fourthly, and lastly, the rim is now soldered or otherwise fastened.

What I claim as my invention, and desire to secure by Letters Patent, is—

A mode or process of manufacturing boxes, cans, and caddies by first coiling, crimping, and beading the rim, then inserting the top or bottom, after which the rim is clamped or held around the top or bottom while it is being soldered or otherwise fastened.

JOHN W. MILLET.
